UNITED STATES PATENT OFFICE

GEORGE BERRY EMERSON, OF BELMONT, MASSACHUSETTS

ORTHOPEDIC MANIKIN CHART

Application filed June 1, 1926. Serial No. 112,853.

My invention relates to problems of corrective orthopedics and particularly to the field of supervised physical culture and more particularly may be stated as having reference to the correction of posture.

While my invention is variously applicable and may be variously used and practiced in its most general aspects, I shall for the purposes of the present invention discuss it in its relation to the more specific field of posture inasmuch as the factors therein involved will be readily interpreted by those skilled in physical welfare, but also because as interpreted in terms of posture my invention becomes more readily appreciated by the general public.

In considering my invention I will first discuss it in relation to means of interpreting to the individual those physical defects which my system is intended to overcome as will be later described. As the former phase of my invention is capable of illustration, I have shown it in the accompanying drawings partly as to structure and partly in diagrammatic outline.

Throughout the specification and drawings like reference characters are employed to indicate corresponding parts, and in the drawings:

Fig. 1 is a view of an anatomical manikin chart in accordance with my invention with manikin in correct posture.

Fig. 2 is a similar view showing an incorrect posture.

Figs. 3 and 4 are similar views showing other postures.

Fig. 5 is a rear view of the device.

Fig. 6 a sectional view of the same.

Fig. 7 is a diagrammatic indication of the normal posture of vital organs of the human body, and

Fig. 8 a similar view of the same in an abnormal or deformed position.

The device shown in the accompanying drawings consists of a chart member or background 1 graduated in vertical lines 2 running vertically of the chart and on each side of a central space 3. Transversely of the chart are a series of lines 4 which may be termed head lines, another series bracketed

as at 5 which may be termed chest lines, a third series indicated at 6 which define the abdominal region, and a fourth series indicated at 7 indicating the knee series. The central region 3 is provided with an elongated slot 8 disposed in the general region of the upper chest adapted to receive a pivot pin 9 which has a position in the assembled figure of manikin corresponding with the seventh cervical. The manikin figure comprises a head member 10 having a chest portion 10¹, a trunk member 11 which is pivoted thereto on a pivot 9, an upper leg member 12 having an abdominal portion 12¹ pivoted at 13 at the position of the hip joint and a lower leg member 14 pivoted to the upper leg member at 15 at the region of the knee joint. The pivot 9 is carried through a slot 8 and provided with a shank or handle 9¹, the joint being held tight by a washer 9² which bears against the rear of the plate 1.

When the figure is mounted on the background 1 and the handle 9¹ grasped by the operator, the manikin can be brought into a perfectly erect position so as to represent a standing figure in proper attitude, lying within the vertical graduations 2 and extending up to the uppermost graduations 4 at the head and with the feet adjacent the lowest line of the chart.

By turning the handle 9¹ and by raising or lowering the pivot 9 in the slot 8 the manikin may be made to assume any one of a large number of characteristic postures. A few of these postures are indicated in Figs. 2, 3 and 4.

The posture in Fig. 1 is a normal posture. In Fig. 2 the manikin posture indicates kyphosis. In Fig. 3 the figure indicates viscerotosis, while in Fig. 4 the posture is one characteristic of lordosis or anterior curvature of the spine.

The degree of deformity in each one of these postures is indicated by the overlap of the manikin on the vertical or horizontal chart lines, so that both lateral deformity and vertical displacement can be observed and noted in scale.

According to my method the posture of the individual to be worked with is analyzed by

the medical or physical director and the manikin brought to a corresponding posture where the graduations on the chart can be noted and recorded. This does two things 5 in that it provides a basis of measurement and study and visualizes for the patient that which he must overcome.

It will be noted that the pivot 9 is connected to the head member 10 which has in its lower 10 part an upper chest portion 10¹. In turning the pivot 9 the position of the head is not only changed but the position of the chest area 10¹ relative to the upper part of the body portion 11 is shifted.

15 In a similar manner I extend the upper leg member 12 to carry an abdominal extension 12¹ which is displaceable relative to the lower part of the body portion 11 to show viscerop-tosis or sagging of the viscera. This is not 20 only important in the matter of appearance but is of vital health importance. For example, this deformity is productive of that most common of human ailments, viz, constipation.

25 I have illustrated diagrammatically in Figs. 7 and 8 the general positions of the viscera in relation to the diaphragm in normal posture (Fig. 7) and an exaggerated de-formed posture, as in Fig. 8. In Fig. 7 it 30 will be seen that the diaphragm D is dome shaped being mechanically a double arch which not only supports the heart and lungs, but supports the whole upper chest region providing freedom for heart and lungs. In 35 this connection, it will be noted that it has a mechanical relation to the spine together with the neck in relation to it as a bodily super-structure, and is of the highest impor-tance not only to physical welfare, but to the 40 higher functions of man.

Considered from below, the diaphragm D has another important function in that it provides a dome or support over the viscera on which life and health is so dependent. In 45 this phase of our consideration, attention is called to Fig. 8 in which the diaphragm D is shown rather in an exaggerated collapsed position. In such a position the liver B and stomach S are permitted to sag, pressing 50 downward on the transverse colon C and ultimately bringing pressure to bear on the intestines generally.

The immediate and obvious result of this is the compression or distortion of the in-55 testines, with the resultant disorders usually known as constipation and with the indirect disorders arising therefrom.

In my corrective method of dealing with these difficulties through the diaphragm I 60 may, without going into detail, point out that it is based upon muscular development, first in the diaphragm muscles and in those asso-ciated with the diaphragm, as constituting supports and control for the diaphragm 65 arches or dome. Second, it contemplates

those muscles which support and control the arch foundations and super-structure, if we may consider these anatomical elements as mechanical.

In this connection the abdominal muscles, 70 such as external and internal oblique and the trans-versalis. I also call attention to the quadratus lumborum and erect or spinal as contributing to the basic support of the dia-phragm. I have devised certain exercises 75 for all these muscles for strengthening and developing them as set forth by me in my posture series which I am publishing and which has been found by me in my work as director of physical education to be well 80 adapted to producing those improvements in posture evidenced by increase in height, cor-rect and easy carriage and by the more im-95 portant resultant effects in prevention and correction of disorders and diseases incident to postural deformity.

While my invention contemplates and is 90 very closely related to systematic exercises as developed in detail in my postural series above referred to, it is probably not neces-sary for me to go into detail as I believe that I have herein indicated sufficient of the gen-100 eral principles involved to cover broadly that portion of my invention.

Referring again to the drawings and this 105 time to Figs. 1 to 4 inclusive, the relation of my method and apparatus will be more ap-110 parent. In my manikin chart the adjust-ments provided produce observable char-acteristic displacements of certain anatomical 115 parts relative to certain other parts so as to be visibly notable and capable of observa-tion and record. In this connection I call at-tention to the movements of that portion of 120 the head member which I have indicated as 125 10¹ and that portion of the leg member which I have indicated at 12¹. The result of de-formity of posture is shown by the lack of 130 coincidence of these parts with the cor-135 responding parts of the trunk member 11.

Referring to Fig. 2 it will be seen that the 140 rear portion of the area 10¹ has begun to over-lap the upper dorsal region so that the mar-ginal line which in Fig. 1 just comes into 145 contact with the first vertical ruling of the chart, has in Fig. 2 overlapped the chart to contact with the third graduation which rep-150 resents an upper dorsal deformity or kypho-sis. This in the case of an average size pa-tient in this posture represents a deformity 155 of three inches.

In Fig. 3 the upper portion 12¹ of the leg 160 member represents the abdominal region and in this figure the abdominal displacement cor-165 responds to the position of the organs as is indicated in Fig. 8. It will be noted in Fig. 170 3 that the resultant forward thrust of the hips in an effort to produce support and gain 175 balance, have resulted in a displacement from 180

the normal shown in Fig. 1 to a degree indicated on the chart of some nine inches.

In each case shown in these two figures, Fig. 2 and Fig. 3, it will be seen that the diaphragm region as shown by the displacement of the lower part of the region 10¹ has slumped and that the distortion of the silhouette outline is the result of that slump or depression of the diaphragm arches.

10 I note particularly, in order to avoid false impression, that the actual anatomical control is based on the diaphragm as a physical structure. In the control of the manikin on the chart the manipulation merely happens 15 to be provided through the cervical pivot 9 which control of the manikin must not be allowed to mislead as to the true anatomy involved. The cervical pivot is merely a convenient mechanical means of producing these 20 movements of the manikin parts which illustrate the importance of the diaphragm control.

I call particular attention to this feature because in my system of corrective exercise 25 I control posture by the diaphragm and by the readjustment of the abnormal spinal curves to normal position. This readjustment of the body structure restores the mechanical balance or inter-relation of the parts 30 which have been designed by nature in accordance with physical laws.

In the manikin the cervical pivot 9 makes a convenient point of adjustment to swing the lower edge of the chest portion 10¹. This 35 movement corresponds with that produced by the tightening of the diaphragm which elevates the chest to normal position while at the same time relieving encroachment upon the viscera.

40 The leg posture both as to hip and as to knee will be found in such a manikin to follow almost automatically the given or adjusted position of the chest. While the figure shown may be considered in general to be 45 a male silhouette it will indicate to those skilled in the art the corresponding feature of the female silhouette.

In presenting my invention for patent I desire to disclaim any intention of unreasonably restricting or limiting the teaching and 50 practice of my system of exercise. In indicating my position, however, I am compelled to reserve to myself all rights in regard to the mechanical devices, charts and 55 to the methods involved in analysis and in my exercises as developed by me.

As regards these I desire to retain reasonable control in order to make sure that the 60 features of my invention are faithfully preserved in practice and where I have provided material equipment to assure myself reasonable control and recompense for such devices or publications as I may make. I have made 65 this statement in filing my application so that

my professional attitude may not be misunderstood.

The device shown and described is capable of a great variety of manipulations and can be made to indicate with very considerable accuracy a large variety of postures or combined postures. Where desired a series of manikins may be provided showing average male and female figures for childhood, youth and middle age, as my corrective system contemplates a reclaiming of normal posture at ages even beyond those usually considered as subject to corrective methods. As above explained, the form of my invention and the practice of or exercises under my method as suggested are to be taken herein as illustrative except as where features are specifically claimed and all modifications and variants are to be considered as within the purview of my invention.

What I therefore claim and desire to secure by Letters Patent is:

1. In an apparatus for posture analysis, a base having a vertically elongated opening, an articulated manikin, a support projected through said opening and rotatable and slideable therein, and charted areas adjacent the contour of the manikin for the analysis of manipulated postural deformities of the articulations of the manikin.

2. In an apparatus of the class described, an articulated manikin including a body member, a head and chest member pivoted to said body member, an upper leg member having an abdominal portion formed at the upper end thereof and pivoted to the body member at the region of the hip joint independently of the pivoting of said head and chest member, and a charted support for said manikin having reference lines for vertical and lateral displacement.

3. In apparatus for posture analysis, an articulated figure having a leg portion provided with an abdominal part projectable into positions representative of postural deformities.

4. In apparatus for posture analysis, a charted background, and an articulated figure having a leg portion provided with an abdominal part projectable relative to said background into positions representative of postural deformities.

5. In apparatus for posture analysis, an articulated manikin including a head and chest member, a body member pivoted thereto, and a leg member pivoted to said body member and having an abdominal part, said head and chest member and said abdominal part being independently and selectively projectable into positions representative of postural deformities.

6. In apparatus for posture analysis, a charted background, an articulated manikin including a head and chest member, a body member pivoted thereto, and a leg member

pivoted to said body member and having an abdominal part, said head and chest member and said abdominal part being independently and selectively projectable relative to said charted background into positions representative of postural deformities.

In testimony whereof I affix my signature.
GEORGE BERRY EMERSON.
